UNITED STATES PATENT OFFICE.

ALEXANDER B. KOKERNOT, OF NEW ORLEANS, LOUISIANA.

REFRIGERATOR.

SPECIFICATION forming part of Letters Patent No. 696,646, dated April 1, 1902.

Application filed October 7, 1901. Serial No. 77,894. (No model.)

To all whom it may concern:

Be it known that I, ALEXANDER B. KOKERNOT, a citizen of the United States, residing at New Orleans, in the parish of Orleans and State of Louisiana, have invented a new and useful Refrigerator, of which the following is a specification.

The present invention relates to refrigerators, and particularly to that class set forth in previous patents granted to me, as follows: January 14, 1890, numbered 419,203 and 419,204; August 5, 1890, numbered 433,867, and June 20, 1893, numbered 500,011 and 500,012. In said class a tube is provided which is detachably fitted across the receptacle containing the material to be cooled, said tube forming a holder for the refrigerant.

In all the constructions set forth in the above-mentioned patents difficulty has been experienced in preventing leakage at the joints between the tube and the receptacle. Another disadvantage resides in locating screw-threads upon the exterior of the tube, which retard the ready insertion and removal of said tube and, furthermore, are liable to be stripped or cut during such operations.

The objects of this invention are to overcome both of the above objections—first, by providing simple means which will insure a liquid-tight joint, and, secondly, locating the necessary screw-threads within the tube where they will not interfere with the removal or replacement of the tube and will be protected from injury.

The preferred embodiment of the invention is fully described in the following specification, and the construction thereof is shown in the drawings which accompany and form a part thereof. The construction thus set forth and described is, however, open to various changes and modifications within the scope of the claims hereto appended.

In the drawings, Figure 1 is a vertical sectional view through a barrel, showing the improved tube in place therein. Fig. 2 is a perspective view of the tube detached. Fig. 3 is a detail perspective view of the removable head. Figs. 4 and 5 are top plan views showing slightly-modified forms of heads. Fig. 6 is a perspective view of the key employed for removing the head shown in Fig. 3.

Similar numerals of reference designate corresponding parts in all the figures of the drawings.

In the present case the refrigerator attachment is shown in connection with an ordinary beer-barrel; but it will be readily understood that it may be employed in receptacles of various kinds. In the drawings the barrel is designated by the numeral 10 and has the usual heads 11, provided with centrally-arranged screw-threaded openings 12, into which are screwed bushings 13, having annular flanges 14, that bear against the outer faces of said heads. Extending across the barrel is the refrigerator-tube 15, the opposite ends of which fit snugly within the bushings 13.

By referring particularly to Fig. 2 it will be seen that this tube is preferably cylindrical in form and has on its exterior face, contiguous to one end, an annular flange 16, provided with notches 17 in its peripheral edge. The end of the tube extending beyond this flange has a plurality of openings 18. The opposite end of the tube is provided with internal threads 19 and is arranged to receive a head 20, the preferred form of which is shown in Fig. 3. This head comprises a cylindrical collar 21, having external threads 22, which coact with the threads 19 in the end of the tube. It is furthermore provided on its exterior face with an annular flange 23, having a pair of oppositely-disposed peripheral notches 24. A wall 25 extends across the collar, and a nipple 26 is secured therein, said nipple having a passage-way 27 therethrough, which is closed by a turning plug 28 or other suitable valve. It will thus be seen that when the head is screwed within the tube the wall 25 closes the end of said tube and the flange extends over the end edge thereof. For the purpose of applying this head a key (illustrated in Fig. 6) is provided, said key comprising a shank 29, having at one end a handle 30 and at the other a ring 31, provided with projecting lugs 32, arranged to engage in the notches 24 of the flange. By applying this device and rotating it in one direction or the other the head can be removed or replaced. In Figs. 4 and 5 slightly-modified forms of head are shown, the same collar 21 and flange 22 being provided, but the notches

24 being located, respectively, in the outer and inner faces of the collar. It will be obvious that a slightly-modified form of wrench or operating device will be necessary, in which 5 case the lugs 32 will be located either on the inner or outer faces of the ring 31, as may be necessary. For the purpose of closing the open end of the tube a cap 33 is provided, which fits over the projecting end of said 10 tube and has an annular flange 34, that rests upon the integral flange 16. Screws 35 or other suitable fasteners detachably connect this cap to the flange. By this means not only is the open end covered, but the side 15 openings 18 are also closed.

The manner of applying the device will be perfectly evident. The head is first detached, and a packing-gasket 36 is located upon the integral flange 16. The tube is 20 then inserted in the barrel, and another gasket 37 is applied to the end thereof, a small portion of which projects beyond the bushing, after which the head is inserted in the manner described and screwed down tightly. 25 As a result the integral flange of the tube will be drawn snugly against the gasket 36, and a tight joint at both ends of the tube will be insured. Furthermore, because of the internal threading of the tube said threads will 30 not interfere in the least with the removal or insertion of the tube and will be protected from injury.

From the foregoing it is thought that the construction, operation, and many advantages of the herein-described invention will 35 be apparent to those skilled in the art without further description, and it will be understood that various changes in the size, shape, proportion, and minor details of construction 40 may be resorted to without departing from the spirit or sacrificing any of the advantages of the invention.

Having thus described my invention, what I claim as new, and desire to secure by Letters 45 Patent, is—

1. In a refrigerator of the class described, the combination with a receptacle, of a tube

passing through the receptacle, said tube being provided with an outstanding annular flange that bears against one of the outer faces of the receptacle, the other end of said tube being internally threaded, a holding-collar screwed into the threaded end of the tube and provided upon its exterior face with an annular flange that bears against the adjacent face of the receptacle, and end walls closing the ends of the tube. 50

2. In a refrigerator of the class described, the combination with a receptacle, of a tube passing through the receptacle, said tube being provided at one end with an outstanding annular flange that bears against the adjacent outer face of the receptacle, the other end of the tube being internally threaded, a holding-collar screwed into the threaded end 60 of the tube and provided upon its exterior face with an annular flange that bears against the adjacent outer face of the receptacle, said collar being provided with a wall that closes the end of the tube, and a cap detachably fitted over the opposite end of the tube. 65

3. In a refrigerator of the class described, the combination with a receptacle having oppositely-disposed openings, of bushings located in the openings, a tube passing through 70 the receptacle and fitting in the bushings, one end of said tube being provided on its exterior face with an annular flange, the opposite end having internal screw-threads, packing interposed between the flange and bushing, a cap located over the end of the tube and detachably secured to said flange, a head screwed into the threaded end of the tube and provided with an exterior annular flange, packing interposed between this latter flange 75 and the adjacent bushing, and a valved vent located in said head.

In testimony that I claim the foregoing as my own I have hereto affixed my signature in the presence of two witnesses.

ALEXANDER B. KOKERNOT.
